STANDPIPE CONNECTION FOR PUMPS

William E. Geer and Elmer R. Wilfley, Denver,
Colo., assignors to A. R. Wilfley and Sons Inc.,
Denver, Colo., a corporation of Colorado

Application March 4, 1940, Serial No. 322,146

7 Claims. (Cl. 285—1)

This invention relates to an improved standpipe connection for centrifugal pumps, and it is particularly an improvement over the disclosure set forth in the patent to A. R. Wilfley, No. 5 1,346,925.

As is well-known to those skilled in the art, it is highly desirable to provide means on a centrifugal pump whereby the standpipe connected with the pump discharge readily may be disconnected and held in a slightly spaced relationship away from the pump casing outlet, when required for the purpose of servicing the pump.

This is particularly true in centrifugal sand pumps where the pump rotor and the casing require servicing or replacement more often than the standpipe itself. Such standpipes may be relatively long and heavy and it would be manifestly impractical to take apart the pipeline itself in order to service the pump.

20 Certain difficulties have been inherent in prior mechanism used for this purpose, because such prior mechanism has provided for a threaded connection with the standpipe. The reason such a threaded connection is undesirable is because 25 the wall of any pipe where a thread is cut into it, is thereby made thinner than other parts of the pipe wall, causing the pipe to wear and weaken due to the abrasive effects of material, particularly sand, discharged through the pipe.

30 Another objection inherent in the prior art is that precise alinement between the standpipe and the pump discharge opening has been difficult or impossible to effect. As a direct result of misalignment between the pump discharge and the standpipe, undesirable eddy currents are set up 35 causing excess friction, inefficient operation, and too rapid wear of the pipe and other parts adjacent the connection.

Still another objection to prior practice has 40 been that means for drawing the standpipe connection securely toward the pump outlet to effect a sealed connection therebetween, have lacked dependable efficiency.

In view of the state of the art and optimum 45 requirements, a principal object of the present invention is to provide means on a centrifugal pump or the like, whereby a standpipe connection with the outlet of the pump may be efficiently and accurately effected.

50 Another object is the provision of such mechanism that can effect a flanged connection with the standpipe, in contradistinction from a threaded connection.

A further object is to provide mechanism of 55 this character that may be used efficiently to lift

the standpipe away from its connection with the pump discharge, and to hold the standpipe in such elevated position so that the pump casing can be removed for service when desired.

Other objects and advantages reside in details 5 of design and construction which will be more fully disclosed in the following description and in the drawing wherein like parts have been similarly designated and in which:

Figure 1 is a general side elevation of a centrifugal sand pump inclusive of the improvements herein set forth; 10

Figure 2 is a fragmentary vertical section of that portion of the mechanism shown in Figure 1 that embodies the present inventive concept, 15 drawn to a larger scale;

Figure 3 is a cross sectional view taken along the line 3—3 of Figure 2; and

Figure 4 is a fragmentary vertical section corresponding to Figure 2, illustrating a slightly modified form of certain details shown in Figure 2. 20

In order clearly to disclose an operative reduction to practice of the present inventive concept, the accompanying drawing will be described in detail. However, it is to be understood that the instant example is intended to be a typical illustration and it should not be construed to express or to imply any particular limitation to this invention, the scope of which is, in reality, measured by the appended claims. 25

In the drawing, reference character 15 denotes a modern centrifugal sand pump as a whole. The pump has a removable rotor casing 16 provided with an upwardly opening discharge 17. A boss-like projection 18 is preferably cast integral with that portion of the general supporting structure of the pump that is not removable with the casing 16. 35

The means for driving the pump and its general operating characteristics need not be here described in detail since they are well-known to those skilled in the art and are no particular part of the present invention. 40

After casting the pump frame inclusive of the boss 18, this boss is drilled with the assistance 45 of a locating jig so that the hole drilled therein is in exact predetermined spaced relationship with the pump discharge 17. A shouldered pin 19 is fitted into the drilled boss 18 and is held therein by a set screw 20, which engages in a groove 50 19a in the pin.

A yoke 21 is provided with semi-circular arms 22 that enclose approximately half of the circumference of a flanged sleeve 23. The yoke has an integral hub 24 that is counterbored to fit 55

accurately over the upper portion of the pin 19, as best shown in Figure 2.

The upper portion of the pin 19 is provided with a keyway 25, and the head of a bolt 26 that is positioned through a side of the hub 24, engages in the keyway after the manner of a key, to provide a guide for longitudinal movement of the yoke with reference to the pin 19.

The lower edges of the arms 22 are provided with three pads so that they bear on the lower flange 23a of the sleeve 23 in a three-point contact.

A screw 27 is positioned centrally through the hub 24 of the yoke 21 and is threaded axially into the pin 19 at the upper end thereof. This screw 27 is provided with a flange 27a, positioned within the bore of the hub 24, and further provided with a nut 28 which is pinned thereto exterior of the hub 24 so that it cannot rotate with reference to the screw after the assembly is effected.

The screw 27 is free to turn in the hub 24, the bore of which is of a size to snugly fit the screw where said bore surrounds it. The upper end of the pin 19 is recessed to admit freely the flange 27a of the screw 27, and the nut 28 is positioned in close proximity to the upper surface of the hub 24 so that it bears thereagainst through the intermediary of a washer 29.

The sleeve 23 is provided with a radially projecting lug 30 that has an elongated opening 31. The lug 30 projects into a corresponding recess 32 in the yoke 21, and the opening 31 in the lug is positioned to align with openings 33 in the yoke 21, so that a bolt 34 may be inserted loosely through said yoke and lug, as best shown in Figure 3. Another lug 35 projects radially from the flanged sleeve 23 immediately above the central portion of the semi-circular yoke arms 22.

A gasket 36 is positioned between the lower flange 23a of the sleeve 23 and the similarly flanged pump discharge 17.

Figure 4 illustrates a modification of the shape and positions of the openings that receive the bolt 34. In this modified form, an opening 31a is positioned in lug 30 and corresponds to the opening 31 hereinbefore described. However, the longitudinal axis of the opening 31a is positioned at an angle from the perpendicular. A series of three openings 33a correspond to the opening 33 and are positioned along a line that is at an angle from the perpendicular, opposite to the axis of the opening 31a and intersecting said axis. This modified arrangement provides for greater adaptability in the relationship of the sleeve 23 and the yoke 21, as is manifest from the drawing.

Assembly and operation

In use, the pin 19 is assembled into the bore 60 of the boss 18 and the set screw 20 is advanced inwardly to engage in the groove 19a, thus preventing axial movement of the pin 19 with reference to its receiving boss 18. When sufficiently tightened, set screw 20 will prevent rotation of the pin 19.

The screw 27 is threaded into the upper end of the pin 19 and the bored hub 24 of the yoke 21 is positioned over the upper end of the pin 19 and the screw 27 so that it encloses the flange 27a and 70 so that the head of bolt 26 engages the keyway 25. Next, the nut 28 is pinned onto the upper end of the screw 27, which projects through the hub.

Since the semi-circular arms 22 of the yoke 21 are open at their outer extremities, the flanged 75 sleeve 23 readily may be inserted between said

arms, bringing the opening 31 or the opening 31a, as the case may be, in the projecting lug 30, into a position to receive the anchor bolt 34 that passes through the yoke 21 and the lug. This anchor bolt 34 serves the purpose of preventing 5 the sleeve 23 from moving outwardly away from the yoke arms 22.

By drawing downwardly on the screw 27 through the intermediary of its pinned nut 28, the entire yoke 21 is drawn downwardly so that 10 the three-point contact of the arms 22 against the lower flange 23a of the sleeve 23, will draw said sleeve down against gasket 36 to effect a sealed connection between the sleeve and the pump discharge. 15

Since the bore in the boss 18 is accurately located with reference to the position of the pump discharge, and since the pin 19, together with the yoke 21 mounted thereon, are rotatable in their mounting, the sleeve 23 will be located accurately with reference to the pump discharge and the three-point bearing of the arms 22 against the flange 23a will insure an optimum seating of the sleeve on the gasket and the gasket on the pump discharge. 25

The upper flange of the sleeve 23 is then joined onto a similar flange on the standpipe, not shown, to complete the assembly.

When it is necessary to remove the casing 16 from the pump for inspection, service or replacement, the screw 27 may be turned by means of its pinned nut 28, in a direction to bring the flange 27a up against the inner surface of the hub 24 to raise the entire yoke 21 so that it will bear against the lug 35 to raise the sleeve 23 and 35 the entire standpipe connected thereabove. This raising of the standpipe need be only a fraction of an inch, which will be enough to break the seal between the sleeve and the pump discharge sufficiently so that the pump casing 16 can be removed. During the time the pump casing is disconnected from the sleeve, the entire standpipe will be held by the yoke 21, and it will be found there is sufficient spring in the standpipe to permit this relatively small movement. 45

Preferably, the nut 28 is threaded onto the upper end of the screw 27 and then pinned to prevent rotation of the nut with reference to the screw. For convenience in disassembly, a set screw, not shown, may be provided through the 50 hub 24 to bear against the screw 27 where the hub surrounds the screw, so that the screw may be held from rotation, when it is desired to unscrew the nut 28 therefrom.

The objects and advantages of this invention are well fulfilled by the structure herein illustrated and described. All threaded connections between standpipe and pump are eliminated; the connection between the standpipe and the pump discharge may be readily and accurately aligned; the seal between the sleeve and the pump discharge is efficiently effected; and the entire standpipe may be lifted from the pump casing and held in this lifted position so that the casing 65 may be removed. 55

The invention is considered to be defined clearly and correctly in the following claims. What we claim and desire to secure by Letters Patent is:

1. In apparatus of the character disclosed, a pump frame, a casing having a discharge opening removably mounted upon the frame, a pin rotatably mounted on the pump frame, a yoke carried upon the pin, and a flanged sleeve en- 70 75

gaged by the yoke and positioned in alinement with the said discharge opening.

2. In apparatus of the character disclosed, a pump frame, a casing having a discharge opening removably mounted upon the frame, a pin 5 rotatably mounted on the frame, a yoke slidably mounted on the pin, a screw positioned through the yoke and threaded into the pin for raising and lowering the yoke with reference thereto, 10 and a flanged sleeve engaged by the yoke and loosely connected therewith in alinement with said discharge opening.

3. In apparatus of the character disclosed, the improvement which comprises a rotatably 15 mounted pin, a yoke carried upon the pin for vertical longitudinal movement relative thereto, a screw engaging the yoke and the pin for so moving the yoke, and a flanged sleeve engaged by the yoke and loosely connected therewith, the 20 yoke having three pads positioned to contact the lower flange of the sleeve, there being a lug projecting from the sleeve above the yoke.

4. In apparatus of the character disclosed, the improvement which comprises an open yoke 25 mounted for both pivotal and axial movements, a sleeve engaged by said yoke, a lug projecting radially from said sleeve, the lug having an elongated opening the axis of which is positioned at an angle with reference to the longitudinal 30 axis of the sleeve, and a connecting member positioned through the yoke and the aperture in the lug.

5. In apparatus of the character disclosed, a pump frame, a casing having a discharge opening removably mounted upon the frame, an annularly grooved pin rotatably mounted on the frame, a set screw engaging in said groove for limiting movement of the pin relative to the pump frame, a yoke having semi-circular open arms and having a hub slidably positioned on the pin, there being a keyway in the pin and a keyway-engaging member on the yoke, a sleeve 10 engaged by the arms of the yoke and positioned in alinement with the discharge opening, means for loosely connecting the sleeve with the yoke, and a flanged screw positioned through the yoke and into the pin for moving said yoke and said 15 sleeve longitudinally with reference to the pin and with reference to said discharge opening.

6. In apparatus of the character disclosed, inclusive of a pump frame, the improvement which comprises a yoke pivotally mounted on the 20 frame, and a flanged sleeve engaged by the yoke for movement thereby relative to said frame.

7. In apparatus of the character disclosed, inclusive of a pump frame, the improvement which comprises a yoke mounted on the frame for 25 pivotal and axial movements, a flanged sleeve engaged by the yoke, and a screw positioned for raising and lowering the yoke and the sleeve with reference to said frame.

30
